UNITED STATES PATENT OFFICE.

LESTER A. WERNERY, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,108,415.

Specification of Letters Patent. Patented Aug. 25, 1914.

Application filed May 29, 1913. Serial No. 770,576.

To all whom it may concern:

Be it known that I, LESTER A. WERNERY, a citizen of the United States, residing in Brooklyn borough, in the county of Kings, city and State of New York, have invented certain new and useful Improvements in Type-Writing Machines, of which the following is a specification.

My invention relates to typewriting machines, and is particularly directed to tabulating devices for carriages. In its preferred form, as herein disclosed, it is applied to a combined column-selecting and tabulating device in which, when a column key is depressed and a decimal key is also depressed, the carriage is released from its escapement, and is drawn along until arrested at the selected decimal place in the selected column.

One object of the present invention is to simplify mechanism of this character, and to so arrange said mechanism that a single kind of column stop may be used interchangeably for every column, and that overthrow or rapid operation of the keys will never select the wrong column or the wrong letter-space in any column. To bring about this result, the carriage of the typewriter may comprise the usual rack bar on which the usual stops are settable. Said stops may be arranged to successively operate a selector bar or a star wheel in such a way that the number of said stops so operating said selector bar or wheel will determine which column-selecting key shall be effective. The first column key may be normally operable to arrest the carriage in coöperation with the decimal keys. As the carriage travels along the first stop on the carriage may move the selector bar or ratchet wheel to such a position that the second column-selecting key if depressed will arrest the carriage; while if said second column-selecting key is not depressed, but some other column key is depressed, the carriage stop corresponding to said column key will move the selector bar so that said other column key will arrest the carriage. To this end, the stops and counter-stops may be normally so positioned that the operation of any key does not move said stops and counter-stops to a position where they will be effective on each other, but the movement of the carriage permits said stops to shift into effective position. This may be brought about by mounting the carriage stops on a rack bar which is so arranged

that the paths of said stops lie normally beyond the counter-stops. When, however, the carriage reaches the selected column, said rack bar shifts so as to bring the next stop thereon into the path of the counter-stop. 65 This next stop, therefore, arrests the carriage at the column thus selected, and if said counter-stop forms one of an array comprising a decimal tabulator, said counter-stop will arrest the carriage at the selected 65 letter-space in the selected column.

Other features and advantages will hereinafter appear.

In the accompanying drawings, Figure 1 is a perspective view of so much of an Underwood typewriting machine, with my improvements applied thereto, as is necessary to the understanding of my invention. Fig. 2 is a sectional side view showing the carriage passing a counter-stop because the rack 70 bar on said carriage is in an ineffective position. Fig. 3 is a view similar to Fig. 2, except that it shows the carriage being arrested by the coöperation of the stops. Fig. 4 is a diagrammatic rear view showing all 75 but the first of the column-selective keys held in the ineffective position shown in Fig. 2. Fig. 5 is a view similar to Fig. 4, showing the last column-stop key lever moving to a position where a decimal stop operated will 80 arrest the carriage. 85

The Underwood typewriting machine comprises a carriage 1 which is drawn along on rails (not shown herein) by a spring barrel 2; said spring is normally held from 90 drawing the carriage along by means of an escapement wheel 3, said wheel coöperating with dogs (not shown herein) operated in any ordinary or desired manner from the character keys (also not shown herein). 95 Said escapement wheel 3 is connected to a pinion 4 working in a rack 5, said rack being pivoted on the carriage at 6 in the usual manner in such a way that it may be swung upward clear of the pinion 4, in which condition the typewriter carriage is drawn along freely by spring barrel 2. For arresting the typewriter carriage when so drawn along freely, there is provided a plurality of tabulating keys forming two groups, one 100 group comprising decimal keys 7 and the other group comprising column-selecting keys 8. Whenever a decimal key 7 is depressed, its key lever 9 swings around a pivot 10 so as to raise upwardly a plunger 105 110

11, the top of which plunger forms a counter-stop 12 which, when projected into the path of a stop 13 on the typewriter carriage, will arrest said carriage. When a 5 decimal tabulating key 7 is thus depressed, it releases the carriage from the escapement mechanism; and for this purpose, each plunger 11 is provided with a shoulder 14, said shoulders underlying a universal bar 15 fast on a rock shaft 16, which rock shaft carries a rock arm 17 having pivoted thereto a link 18. The downward movement of said link 18, whenever a decimal tabulating key is depressed, swings a pivoted lever 19 so 10 that a roll 20 on the end thereof underlying the rack 5, lifts said rack clear of the pinion 4, thus releasing the carriage, as above described.

In the form of the invention herein illustrated, the stops 13 on the carriage are normally held so that their paths of movement, 20 lie clear of the counter-stops 12; but, by operation of the column-selecting keys, any selected stop 13 may be swung, till its path 25 will strike the counter-stop 12, and so will arrest the carriage. To bring this about, the rack bar 21 on which said stops 13 are settable is pivoted at 22 to an extension 23 of the typewriter carriage, and is normally 30 swung upwardly around said pivot by means of a spring 24.

The rack bar 21 may be swung downwardly around its pivot 22 by means of any column-selecting key 8. Said column-selecting keys 8 (except the first) are, however, normally prevented from being depressed by means of a selector bar 25 which overlies their rear ends, the key levers 26 of said column-selecting keys 8 being pivot-40 ed at 27. This selector bar 25 is moved by the typewriter carriage so as to allow the column-selecting keys to be operated at times which may be determined by the stops 13 set on the rack bar 21. To bring this 45 about, the selector bar 25 is slideable in guides 28, and said selector bar, when moved along, successively brings a notch 29 in its lower portion over the levers of the column keys, as seen in Figs. 4 and 5. When said 50 notch 29 is over any key lever 26, it permits that lever to be operated thus swinging the rack bar 21 downwardly so that the stops 13 thereon will strike any projected counter-stop 12. To do this, the key lever 26 moves 55 upwardly a universal bar 30, so that a link 31 attached to said universal bar will swing upwardly a rock arm 32, thereby depressing a rock arm 33 so that a roller 34 on said last-named rock arm, which rides on an 60 extension of the rack bar 21, will depress said rack bar, thus swinging the stops on said bar to a point where they will be intercepted by the counter-stops 12 in the travel of the typewriter carriage.

5 The rock arms 32 and 33, it will be seen,

are fast on a shaft 35 which is journaled on an extension 36 of the casing carrying the decimal tabulating device. The universal bar 30 is guided in slots 44 at each end thereof, and is preferably provided with a 70 link 31 at each end. For operating the selector bar 25, there is provided thereon a rack 37 which meshes with a pinion 38 at the bottom of a shaft 39, said shaft carrying at its upper end a star wheel 40, which star wheel stands adjacent the rack bar 21 in such a position that the teeth of said star wheel are successively intercepted and turned by the stops 13. The star wheel 40 and pinion 38 are so proportioned that, 75 whenever one stop 13 turns the star wheel 40 in passing it, it moves the selector bar 25 the distance between the centers of two column key levers 26, thus moving the edge of the notch 29 from one column stop to 80 the next.

The star wheel 40 is preferably placed so that it will be turned by the stops 13 either before or after they reach the array of decimal stops 12. As shown herein at Fig. 1, 90 said star wheel is so placed that it will intercept the first stop 13 after said stop has passed all the decimal stops 12. With this construction the selector bar 25 should be arranged as shown at Fig. 4, in which 95 figure the first column key lever can be depressed at any time. Thus, to arrest the carriage in the first column, the first column key and the desired decimal key are depressed. When the typewriter carriage carries its first stop 13 beyond the decimal stops, said stop turns the star wheel 40 and thereby moves the selector bar along bringing its notch above the various column key levers successively and therefore releasing 105 them as the successive stops turn the star wheel.

From the above description, it will be seen that to arrest the typewriter carriage, the column key must be held down when a 110 decimal key is depressed. The typewriter carriage will be released from its escapement mechanism by the depressed decimal key and will travel along freely, turning the star wheel 40 as said star wheel is struck 115 by the stops 13, until the desired column is reached. At this moment the notch 29 in the selector bar 25 releases the column key lever which completes its operation by rising up at its rear end under the pressure 120 of the operator's finger, thus swinging down the rack bar 21 with its stops 13, so that said stops will be intercepted by the decimal stop 12 which has been projected, and thus arrest the carriage.

In order to accurately space the column-selecting keys, they pass between the teeth of a comb 41 at a point adjacent the selector bar 25.

The extension of the rack bar 21 which 130

is engaged by the roller 34 may be in the form of a bar 42 which overlies said rack bar, and is attached thereto by means of brackets 43.

5 During the return of the carriage to position for writing a new line, the column stops 13 rotate the star wheel 40 backwardly and thereby return the selector bar 25 to normal position.

10 Variations may be resorted to within the scope of the invention, and portions of the improvements may be used without others.

Having thus described my invention, I claim:

15 1. In a typewriting machine, the combination with a carriage, of a rack bar on said carriage, stops on said rack bar, a counter-stop for said carriage, a pivot on which said rack bar swings, so that it normally holds the stops thereon out of the path of said counter-stop, selectively operable keys, and means operated by the keys for depressing said rack bar at a selected column in the travel of the carriage corresponding to the selector key for causing said stops to be intercepted by the counter-stop.

2. In a typewriting machine, the combination with a carriage and a rack bar thereon, of stops settable on said rack bar, counter-stops on the frame of the typewriter, a spring normally holding said rack bar to carry its stops clear of said counter-stops, a wheel turned by the passing stops during the travel of the carriage, a selector bar moved by said wheel, and column-selecting keys to operate the counter-stops and controlled by said selector bar.

3. In a typewriting machine, the combination with a carriage and a rack bar thereon, of stops settable on said rack bar, a pivot on which said rack bar turns, a counter-stop on the frame of the typewriter, means normally holding said rack bar so that the stops thereon are out of the range of the counter-stop, column-selecting keys normally incompletely operable, a selector bar for determining when a column key shall become completely operable, and a wheel turned by said rack stops for operating said selector bar.

4. In a typewriting machine, the combination with a carriage and a rack bar thereon, of stops settable on said rack bar, a pivot on which said rack bar turns, a counter-stop on the frame of the machine, means for holding said rack bar to keep its stops from engaging the counter-stop, keys adapted to move said rack bar to carry the stops thereon into the path of the counter-stop, and a selector bar moved by said stops for determining which of said keys shall become effective at a given time.

5. In a typewriting machine, the combination with a carriage and a rack bar pivoted thereon, of stops settable on said rack

bar, a counter-stop out of the path of which said rack stops are normally held, a series of column-selecting keys, a universal bar moved by said column-selecting keys, and a selector bar operated by said stops for determining what column-selecting key shall become effective on said universal bar to make said rack stops effective.

6. In a typewriting machine, the combination with a carriage, a rack bar thereon, and stops settable on said rack bar, of a wheel turned by said stops, key-operated counter-stops, and means controlled by said wheel for determining when a stop shall become effective.

7. In a typewriting machine, the combination with a carriage and a movable rack bar thereon, of stops settable on said rack bar, a counter-stop with reference to which said rack stops are normally ineffective, a wheel turned by said rack stops, column-selecting keys, and means under the joint control of said column-selecting keys and said wheel for moving said rack stops into effective position.

8. In a typewriting machine, the combination with a carriage, of stops settable thereon, a selector bar moved by said stops, and column-selecting keys for determining in which column said carriage shall be arrested, said keys operable as determined by said selector bar.

9. In a typewriting machine, the combination with a carriage, of stops settable thereon, a wheel moved by said stops, a selector bar moved by said wheel, column-selecting keys, and means for determining by said selector bar which of said column-selecting keys shall be effective on said stops to arrest said carriage.

10. In a typewriting machine, the combination with a carriage and an array of decimal tabulating keys, of an escapement for said carriage, means for releasing said carriage from said escapement by the operation of said keys, column-selecting keys, stops on said carriage by which said decimal stops may arrest said carriage in various columns, and a selector bar moved by said stops for determining when said column-selecting keys shall become effective.

11. In a typewriting machine, the combination with a carriage and stops settable thereon, of counter-stops normally out of the path of said carriage stops, column-selecting keys for moving said carriage stops into the path of said counter-stops, a universal bar for so moving said stops, and a universal selector bar operated by said stops for determining when a column-selecting key shall become effective.

12. In a typewriting machine, the combination with a carriage and stops interchangeably settable thereon, of column-selecting keys, a universal bar operated by

said column-selecting keys, counter-stops, means for moving said carriage stops into the path of said counter-stops by said universal bar, and a selector bar moved by said stops for determining which column-selecting key shall be effective.

13. In a typewriting machine, the combination with a carriage, of stops settable thereon, a counter-stop, a single selector bar operated by said stops in such a way that mere moving of a stop has a corresponding effect on the selector bar, column-selecting keys controlled by said selector bar, a universal bar in position to be moved by the column-selecting keys and moved by the effective column-selecting key, and means operated by the universal bar to effect an operative relation between a stop on the carriage and said counter-stop.

20 14. In a typewriting machine, the combination with a carriage and stops settable thereon, of column-selecting keys, a universal connection between said column-selecting keys and said stops for moving the stops to operative position, counter-stops, and decimal keys for operating the counter-stops.

15. In a typewriting machine, the combination with a carriage, of a rack bar pivoted thereon, stops settable on said rack bar, a spring holding said rack bar, counter-stops into the path of which said rack bar may swing its stops, a selector bar operated by said first-mentioned stops, and column-selecting keys of which said selector bar determines which key shall be effective.

16. In a typewriting machine, the combination with a set of decimal tabulating keys forming one element, of a set of column-selecting keys forming another element, a universal bar connected to one element, a universal bar connected to the other element, a carriage adapted to be positioned by said elements when an operating pressure is concomitantly applied to a key of each set, an escapement for said carriage, means for releasing said carriage from said escapement by the universal bar connected to the decimal tabulating keys, and means for selectively making the column-selecting keys operable 50 to position said carriage by the other universal bar.

17. In a typewriting machine, the combination with a carriage and a rack bar pivoted thereon, of a lever for swinging said rack bar, a stop settable on said rack bar, counter-stops into the path of which said lever moves said stop as it swings said rack bar, column-selecting keys to project the counter-stops, a universal bar common to 60 said column-selecting keys, links by which said universal bar is carried, and rock arms forming an extension of said lever and connected to said links for swinging said rack bar from said keys.

65 18. In a typewriting machine, the combi-

nation with one group of keys, of another group of keys, stops individually operated by one group, a universal bar common to the other group, and an array of stops operated by said universal bar.

70

19. In a typewriting machine, the combination with a carriage, of separated stops, tabulating keys for individually moving said separated stops to effective position, tabulating keys for moving a group of stops to effective position, means operated by the carriage and coöperating with said last-mentioned keys to selectively determine which stop of said group shall engage the said effective separated stop to arrest the typewriter carriage.

75

20. In a typewriting machine, the combination with a carriage, of a gang of decimal tabulating stops, column stops on the carriage, a wheel moved by each column stop after said column stop has passed all of said decimal stops, keys for projecting the decimal tabulating stops to operative position, keys to actuate the column stops, and means operated by said wheel to selectively control 90 the operation of the column stops.

85

21. The combination of a rack bar, column stops thereon, column-selecting keys, a universal bar controlled by said keys, means operated by said universal bar to move the rack bar in one direction to bring the column stops to operative position, denominational keys, stops projected thereby into the path of the operated column stops, means to move the rack in a different direction, restraining means opposing such movement, a universal bar operated by said denominational keys, and means controlled by said last-named universal bar to release the rack from said restraining means and permit it 100 to be moved in said different direction and bring a column stop into engagement with an operated denominational stop.

95

22. In a typewriting machine, the combination with a carriage, of column stops settable thereon, column-selecting keys, a universal bar operated by said column-selecting keys for controlling said column stops, a selector bar controlling said keys and operated by said column stops so that the mere shifting of a column stop one letter space correspondingly shifts the point in the travel of the carriage at which the selector bar is operated, decimal tabulating keys, and stops operated thereby and coöperating with said column stops.

110

23. In a typewriting machine, the combination with a carriage, of a rack bar mounted thereon for movement in a direction transverse to the direction of travel of the carriage, column stops settable on said rack bar, a series of denominational stops, keys to selectively project the denominational stops, said rack bar being normally held with its stops out of the path of the pro-

115

120

125

130

jected denominational stops, column-selecting keys, a universal bar operated thereby, a swinging frame connected to said universal bar and having a running connection 5 with a track carried with the rack bar for moving the latter and bringing the stops thereon into position to be intercepted by a projected denominational stop when said universal bar is operated, a selector bar in 10 position to prevent the column-selecting keys from actuating said universal bar, an escapement controlling the travel of the carriage, means operated by the denominational keys to release the carriage from its escape- 15 ment and permit it to run forward, and a device to operate said selector bar, said device having a step-by-step operation imparted to it by the column stops during said movement of the carriage, said selector bar 20 thereby moved to release the column-selecting keys in succession as the carriage reaches positions corresponding to the setting of said column stops, thereby permitting each column stop to be moved to operative position 25 when the carriage reaches a column position corresponding to a selected column selecting key to which an operating pressure is applied.

24. In a typewriting machine, the combination with a carriage, of a series of column stops settable thereon, column-selecting keys, universal means operable by said keys to move the series of column stops to an operative position, column-selecting means operated by the carriage to control the operation of said keys and permit each to operate said column stops when the carriage has reached a position corresponding to the selected key, and a counter-stop into the path 40 of which the column stops are moved by said keys.

25. In a typewriting machine, the combination with a carriage, of a series of column stops settable thereon, column-selecting keys, universal means operable by said keys to move the series of column stops to an operative position, column-selecting means operated by the carriage to control the operation of said keys and permit each to operate said column stops when the carriage has reached a position corresponding to the selected key, a counter-stop into the path of which the column stops are moved by said keys, denominational stops, denominational 50 keys to selectively project the denominational stops into position to intercept the column stops, an escapement mechanism for the carriage, and a universal bar operated by the denominational keys to release the carriage from its escapement mechanism.

26. In a typewriting machine, the combination with a carriage, of a rack bar thereon, column stops settable on said rack bar, said rack bar movable on the carriage to 65 move the stops into and out of operative

position, column-selecting keys, a universal bar operated by said keys, means operated by said universal bar to move the rack bar to operative position, denominational stops, keys to selectively project said denominational stops into the path of the column stops, a selector bar to prevent the column-selecting keys from operating said universal bar, and means operated by the column stops to impart a step-by-step movement to 70 said selector bar as the column stops successively reach a predetermined point during the travel of the carriage, said column-selecting keys being successively released from said selector bar by said step-by-step movement, thereby permitting each column-selecting key to move the column stops to operative position when the carriage has reached a position corresponding to the said column-selecting key.

27. In a typewriting machine, the combination with a carriage, of a rack bar thereon, column-stops settable on said rack bar, said rack bar movable on the carriage to move the stops into and out of operative position, column-selecting keys, a universal bar operated by said keys, means operated by said universal bar to move the rack bar to operative position, denominational stops, keys to selectively project said denominational stops into the path of the column stops, a universal selector bar to prevent operation of the column-selecting keys, a rotatable shaft geared to said selector bar, and a wheel on said shaft to which a step-by-step rotation is imparted by the column stops during the travel of the carriage, whereby the selector bar is given a step-by-step movement to successively release the column-selecting keys and permit the column stops to be moved to operative position when the carriage reaches predetermined points corresponding to the released keys.

28. In a typewriting machine, the combination with a carriage, of a rack mounted thereon to swing in a direction transverse to the direction of travel of the carriage, a group of column stops on the rack, column-selecting keys corresponding to said stops, denominational stops, keys to selectively project the denominational stops into position to intercept the column stops, universal means operated by the column-selecting keys to swing the rack, and thereby move the column stops to operative position, and column-selecting means preventing the operation of each column-selecting key during a portion of the carriage travel, said column-selecting means operated by the carriage to determine the point during the travel of the carriage at which each column-selecting key is operable to swing said rack.

29. In a typewriting machine, the combination with a carriage, of a rack mounted thereon to swing in a direction transverse to

the direction of travel of the carriage, a group of column stops on the rack, column-selecting keys corresponding to said stops, denominational stops, keys to selectively project the denominational stops into position to intercept the column stops, universal means operated by the column-selecting keys to swing the rack and thereby move the column stops to operative position, and a controlling device operated step by step by the column stops as the carriage in its travel reaches positions corresponding to the setting of the stops on the rack, said controlling device preventing the operation of the column-selecting keys until the carriage reaches said positions, and when said positions are reached, releasing said column-selecting keys and permitting them to swing the rack and move the column stops into position to be intercepted by the projected denominational stops.

30. In a typewriting machine, the combination of a series of column stops, a carrier on the carriage along which said stops are

individually adjustable to different column 25 positions, a counter-stop, said column stops being normally out of the path of the counter-stop, a series of column-selecting keys corresponding to the respective column stops, means operated by said keys to move 30 the series of column stops into the path of the counter-stop, and a column-selecting device to prevent said keys from swinging the column stops to an operative position, said selecting device operable by the carriage and 35 coöperating with any selected key to permit the column stops to be moved to operative position when the carriage reaches the position determined by the adjustment of the stop corresponding to the selected key, 40 whereby the keys are selectively operable to cause the carriage to be stopped at the positions corresponding to the adjustment of the column stops.
